RECOVERY OF GASOLINE

Raymond C. Lassiat, Swarthmore, Pa., assignor
to Houdry Process Corporation, Wilmington,
Del., a corporation of Delaware

Application February 27, 1937, Serial No. 128,112

6 Claims. (Cl. 196—10)

This invention relates to the production, separation and recovery of light or low boiling hydrocarbons especially liquid hydrocarbon mixtures in the gasoline boiling range suitable for use as motor fuel in internal combustion engines.

One object of the invention is to recover from a stream of light hydrocarbons the maximum quantity which can be made available for use as liquid motor fuel or gasoline. Another object is to combine or intercombine a series of operations or process steps in such manner as to produce directly therefrom or thereby gasoline of desired vapor pressure. Another object is to effect the above results in a continuous operation on light hydrocarbons having an end point suitable for motor fuels, for example approximately 400° F., which light hydrocarbons may be separated by fractionation or otherwise from the products of a distillation, catalytic transforming, or thermal cracking zone to which hydrocarbons are charged from any source, either in natural or derived state or blended. Other objects will be apparent from the detailed description which follows.

The initial material to be treated may be derived from any source of hydrocarbons including mineral oil, shale, coal, lignite, etc. and is preferably in the form of a composite hydrocarbon stream comprising or including some hydrocarbons in the desired boiling range. According to the invention, such a stream is subjected to a series of separating and/or fractionating operations to segregate therefrom a low vapor pressure gasoline and a cut composed substantially of hydrocarbons of the three and/or four carbon atom group. This cut is subjected to polymerization to convert at least a part of the unsaturates therein into liquid hydrocarbons and the resulting products, both liquid and gaseous, are utilized to increase the quantity of low vapor pressure gasoline and to raise the vapor pressure of the latter to any desired extent, as for example to that of commercial gasoline. The products of the polymerizing operation may be fed back into the system at one or several points as may be desirable for economical operation and for highest recovery of liquid products, including dehydrogenation of some or all of the gaseous material issuing from the polymerization zone.

The nature of the invention and the manner of its use is illustrated diagrammatically in the accompanying drawing, the single figure of which shows a complete operative circuit for producing

gasoline of desired vapor pressure and indicates a number of alternative modifications.

In the drawing, a composite stream of hydrocarbons of wide boiling range and from any source, including a vaporizing, transforming or cracking zone, as indicated diagrammatically, is conducted by line 1 to a primary separating zone A containing apparatus of any known or desired type. In the present instance, a fractionating tower or column 2 is indicated, wherein heavier or high boiling hydrocarbons are condensed and from which they are conducted away by line 3, for example, as fuel oil or cycle stock for storage or for immediate consumption or further treatment. An overhead cut or fraction, preferably comprising all hydrocarbons in the gasoline boiling range and lighter, is conducted from the top of the tower 2 by line 5 through condenser 4 to separator 5, whence condensate leaves by line 6 which has a branch 7, if desired, for conducting part of the condensate as reflux to the upper end of fractionator 2 to control the operating temperatures therein. Gaseous material leaves the upper end of separator 5 by line 8, which conducts the same, with or without additional gaseous material added by branch lines 9 and 10, to an absorption zone B containing apparatus of any suitable or desired type. The absorption system diagrammatically indicated utilizes a circulated liquid medium which enters the top of absorber or stripping tower 11 and is passed countercurrent to the gaseous charge admitted by line 8, the rich absorbent liquid passing from the bottom of tower 11 through heat exchanger 12 and heater 13 into the lower end of vaporizer 14, where the absorbed gasoline vapors are released to leave the top of the absorber by line 15, the lean absorbent liquid then being pumped back from the bottom of vaporizer 14, through heat exchanger 12 and cooler 16, to be again discharged into the top of stripping tower 11. Fixed and incondensable gases, such as hydrogen and methane, leave the top of tower 11 by line 17 and are entirely withdrawn from the system to be burned as fuel gas, to be used as a gaseous reducing medium, or for any other purpose. The gasoline vapors in line 15 are sent into condenser 18, whence the condensate is conducted by line 19, to be added to the condensate in line 6, but a part may be sent back by line 18, if desired, into the top of vaporizing tower 14 as reflux.

The gasoline condensate from separator 5, together with the condensate brought from absorption zone B by line 19, is conducted by line 6 to a stabilizing or debutanizing zone C having

apparatus of any suitable or desired type to separate out a gasoline having a low vapor pressure. The stabilizing apparatus illustrated comprises a heater 19 and a debutanizing or fractionating tower 20, the low vapor pressure gasoline being withdrawn as a condensed bottoms fraction by line 21, while the lighter hydrocarbons of the C₂, C₃ and C₄ carbon groups leave tower 20 by overhead line 53, to be conducted through condenser 22 into gas separator 23. Any fixed and incondensable gases are vented from the top of separator 23 into line 9, which joins line 8 leading to absorption zone B. A portion of the condensate from separator 23 may be sent as reflux back into stabilizer 20 by line 24, while the remainder is sent by line 25 to separating zone D, having apparatus of any known or desired type to remove from the condensate the lighter hydrocarbons which are not readily susceptible of polymerization, including those of the C₂ carbon group with at least a part of the C₃ group. The apparatus indicated comprises a heater 26 and a fractionating tower 27. The hydrocarbons to be rejected leave tower 27 by line 28 as an overhead fraction and are withdrawn from the system for such use as may be desired. Reflux to control the operation of the tower will be admitted by line 29 from any suitable source. The tower is operated so as to produce a selected bottoms or liquid fraction which leaves the tower by line 30 and contains a maximum quantity of unsaturates suitable for polymerization into hydrocarbons in the gasoline boiling range, including the hydrocarbons of the four carbon group. This fraction is utilized both to increase the quantity of gasoline recoverable from the original charging material and the unpolymerized part can be added to the low vapor pressure gasoline in line 21 to adjust the vapor pressure of the same as may be desired, for example to raise the vapor pressure to that of commercial gasoline. Accordingly, line 30 leads to a polymerizing zone E containing apparatus of any suitable or desired type for producing the desired result. Since the selected fraction is already in liquid phase, it is advantageous to use a low temperature liquid phase operation. One operation of this character which is quite suitable utilizes pressures up to 500 pounds, a temperature range of 50 to 300° F., and a catalytic mass having suitable selective adsorptive properties, such, for example, as certain blends of silica and alumina of natural or artificial origin. However, any other suitable polymerizing operation, whether liquid phase or vapor phase, may be utilized in zone E.

The products of the polymerizing operation leave the polymerizing zone by line 31, which conducts them to a cooler or condenser 32. If the liquid polymers formed do not contain substantial amounts of material boiling above the gasoline boiling range, and if the unconverted gaseous material is substantially free of fixed and incondensable gases and hence suitable for absorption by low vapor pressure gasoline to raise the vapor pressure of the same to the desired amount, all liquid and gaseous materials leaving cooler 32 may be sent by line 33 to be added to the low vapor pressure gasoline in line 21, as indicated. If it is desirable to separate the products of polymerization into gaseous and liquid hydrocarbons, the same may be conducted from cooler 32 by line 34 to separator 35. The liquid fraction from the bottom of separator 35 may be conducted by line 36 and thence sent by branch line 37 to be added

to the condensate in line 6 passing to separating or stabilizing zone C, or some or all of the condensate may be sent by branch line 38 to be added to the material in primary separating zone A, in this instance to be admitted as reflux into tower 2 at any suitable level, depending upon its boiling range. The gaseous material leaves separator 35 as an overhead fraction by line 39, which conducts it through a cooler or condenser 40, from which some of it (if the cut is rich in unsaturates) may be sent back by line 41 to be added to the selected cut in line 30 for recirculation through the polymerizing zone E. Any desired part or all of the gaseous material may also be sent by line 42 to be added to the low vapor pressure gasoline in line 21 to raise the vapor pressure of the same to the desired extent. Some or all of the overhead cut may also be withdrawn from the system by line 43 for such other use as may be desired. If the gaseous cut is of large volume but poor in unsaturates, some or all of it may be sent by line 44 to and through a gas cracking or dehydrogenating zone F containing apparatus of any known or desired type, either thermal or catalytic, which will convert the gases into unsaturates. A dehydrogenating operation suitable for use in zone F is one effected at low pressure, with a catalyst comprising a blend of chromium oxide and alumina maintained at a temperature in the range of 900° to 1000° F. The products of dehydrogenating zone F are conducted by line 45 through cooler 46 and then by line 47 into branch line 10 which joins line 8 leading to absorption zone B, or, alternatively, may be conducted by branch line 48 to join line 51 in advance of condenser 4.

If polymerizing zone E produces fixed gases, and it is undesirable to use the circuit which includes dehydrogenation zone F, then suitable gas separating equipment (not shown) may follow cooler 40, the vent to the separating equipment being suitably joined to branch line 10 or branch line 9, so that fixed and incondensable gases and vapors entrained therewith will be conducted to absorption zone B.

Saturated hydrocarbon gases suitable for cracking into unsaturates may be admitted to the system in advance of dehydrogenating zone F, as by valved branch line 49. Light hydrocarbon gases, such as those vented from the separator mentioned in the preceding paragraph, or which it may be desirable to add to the system from any outside source, may be conducted thereto, as by line 50 leading into line 10 in advance of absorption zone B.

I claim as my invention:

1. Process of recovering a maximum quantity of commercial gasoline from a composite hydrocarbon stream which comprises subjecting said stream to a series of fractionating operations to segregate therefrom a low vapor pressure gasoline and a cut composed substantially of hydrocarbons of the four carbon group, subjecting said cut under polymerizing conditions to a polymerizing operation to convert at least a part of the unsaturates therein into liquid hydrocarbons utilizing the liquid polymers from said polymerizing operation as reflux in one of said fractionating operations so as to augment the quantity of said low vapor pressure gasoline, and adding to said gasoline sufficient gaseous material from said polymerizing operation to raise the vapor pressure thereof.

2. Process of recovering a maximum quantity of commercial gasoline from a composite hydro-

carbon stream which comprises subjecting said stream to a series of fractionating operations to segregate therefrom a low vapor pressure gasoline and a cut composed substantially of hydrocarbons of the four carbon group, subjecting said cut under polymerizing conditions to a polymerizing operation to convert at least a part of the unsaturates therein into liquid hydrocarbons, adding the liquid polymers from said polymerizing operation to the material charged to one of said fractionating operations so as to augment the quantity of said low vapor pressure gasoline, adding a part of the gaseous materials from said polymerizing operation to said gasoline to raise 10 the vapor pressure thereof and recycling the remainder of said gaseous material directly through said polymerizing operation.

3. Process of recovering a maximum quantity of commercial gasoline from a composite hydrocarbon stream which comprises subjecting said stream to a series of separating operations to segregate therefrom a low vapor pressure gasoline and a cut composed substantially of hydrocarbons of the four carbon group, subjecting said cut under polymerizing conditions to a polymerizing operation to convert at least a part of the unsaturates therein into liquid hydrocarbons, utilizing the liquid polymers from said polymerizing operation as reflux in effecting the segregation of said low vapor pressure gasoline and to augment the quantity of the latter, adding a part of the gaseous material from said polymerizing operation to said gasoline to raise the vapor pressure thereof, and sending the remainder of the gaseous material from said polymerizing operation back into the system in advance of one of said separating operations.

4. Process of recovering a maximum quantity of commercial gasoline from a composite hydrocarbon stream which comprises subjecting said stream to a series of separating operations to segregate therefrom a low vapor pressure gasoline and a cut composed substantially of hydrocarbons of the four carbon group, subjecting said cut under polymerizing conditions to a polymerizing operation to convert at least a part of the unsaturates therein into liquid hydrocarbons, utilizing the liquid polymers from said polymerizing operation as reflux in effecting the segregation of said low vapor pressure gasoline and to augment the quantity of the latter, adding a part of the gaseous material from said polymerizing operation to said gasoline to raise the vapor pressure thereof, subjecting the remainder of the gaseous material from said polymerizing

operation to a dehydrogenating or gas cracking operation to increase the unsaturates therein and adding the products of the dehydrogenation operation to the hydrocarbon stream fed to one of said separating operations.

5. In the treatment of a composite hydrocarbon stream containing hydrocarbons within, above and below the gasoline boiling range to recover a maximum quantity of liquid hydrocarbons in the gasoline boiling range, the 10 process steps which comprise separating from the stream hydrocarbons in the gasoline boiling range and lighter, removing from the last named hydrocarbons the fixed and incondensable gases contained therein, separating the remaining hydrocarbons into low vapor pressure gasoline and lighter hydrocarbons primarily of the two, three and four carbon atom groups, removing from said lighter hydrocarbons a fraction composed primarily of those in the four carbon atom group, subjecting the latter to a polymerizing operation to convert at least a part of the unsaturates contained therein into liquid hydrocarbons, adding liquid polymers from the polymerizing operation to one of said separating steps to increase the 25 yield of gasoline, using a part of the gaseous material from the polymerizing operation to adjust the vapor pressure of said low vapor pressure gasoline, and recycling the remainder of said gaseous material from the polymerizing operation through 30 the latter.

6. In the treatment of a composite hydrocarbon stream to recover a maximum quantity of liquid hydrocarbons in the gasoline boiling range the process steps which comprise separating from the stream hydrocarbons in the gasoline boiling range and lighter, removing from the last named hydrocarbons the fixed and incondensable gases contained therein, separating the remaining hydrocarbons into low vapor pressure gasoline and 40 lighter hydrocarbons of the two, three and four carbon atom groups, removing from said lighter hydrocarbons those in the four carbon atom group, subjecting the latter to a polymerizing operation to convert at least a part of the unsaturates into liquid hydrocarbons, utilizing liquid polymers from the polymerizing operation to assist in the first separating step and thereby augment the quantity of low vapor pressure gasoline, and utilizing a part of the gaseous material 45 from the polymerizing operation to adjust the vapor pressure of the low vapor pressure gasoline and adding the remainder to the charge to said first removing step.
